UNITED STATES PATENT OFFICE

157,205

ILLUMINATING TABLE

Lewis J. Reynolds, Houston, Tex.

Application February 20, 1948, Serial No. 144,640

Term of patent 14 years

(Cl. D33—14)

To all whom it may concern:

Be it known that I, Lewis J. Reynolds, a citizen of the United States of America, residing at Houston, Harris County, State of Texas, have invented a new, original, and ornamental Design for an Illuminating Table, of which the following is a specification, reference being made to the accompanying drawing, forming a part thereof.

Figs. 1 and 2 are perspective views of the front and rear, respectively, of the illuminating table embodying my new design.

I claim:

The ornamental design for an illuminating table, substantially as shown.

LEWIS J. REYNOLDS.
